UNITED STATES PATENT OFFICE

93,078

DESIGN FOR A SPOON OR SIMILAR ARTICLE

Marx J. Wiese, Providence, R. I.

Application April 3, 1934, Serial No. 51,303

Term of patent 3½ years

To all whom it may concern:

Be it known that I, MARX J. WIESE, a citizen of the United States, and resident of Providence, in the county of Providence and State of Rhode Island, have invented a new, original, and ornamental Design for a Spoon or Similar Article, of which the following is a specification, reference being had to the accompanying drawing, forming part thereof.

In the drawing:

Fig. 1 is a front view of a spoon or similar article showing my new design;

Fig. 2 is a back view of Fig. 1; and Figs. 3, 4 and 5 are sections on the lines 3—3, 4—4 and 5—5 of Fig. 1.

I claim:

The ornamental design for a spoon or similar article, substantially as shown.

Signed at Providence, in the county of Providence and State of Rhode Island, this 2d day of April, A. D. 1934.

MARX J. WIESE.
